(57) **CLAIM**

The ornamental design for the display panel with a generated image for a PDA, as shown and described.

DESCRIPTION

FIG. 1 is a perspective view of a display panel with a generated image for a PDA;

FIG. 2 is a front view of the display panel with a generated image for a PDA of FIG. 1; and,

FIG. 3 is an enlarged front view of the display panel with a generated image for a PDA of FIG. 1.

The broken line showing of the display panel is included for the purpose of illustrating portions of the article and forms no part of the claimed design.

1 Claim, 3 Drawing Sheets

FIG. 1

FIG. 2**FIG. 3**
